GUIDO HORN, OF WEISSENSEE, NEAR BERLIN, GERMANY

ROUND BRAIDING MACHINE

Application filed December 28, 1928, Serial No. 329,042, and in Germany December 29, 1927.

The invention relates to round braiding machines with two series of spool carriers traveling in opposite directions in circular paths. It is well known that a thread traveling or sweeping about the centre of a machine, describes a rotary movement about its own axis. The invention particularly aims at avoiding this rotation and the twist resulting therefrom, and attains this aim by causing the traveling carriers to be so rotated continuously with the aid of gear-wheels, that the rotation or twisting of the thread caused by the traveling or circling round the centre of the machine is neutralized, i. e. in other words that a return-movement or compensating movement is effected. Such a machine will be found particularly useful for the braiding of telephone-cable, connecting the receiver with the telephone-apparatus proper, as well as for cables for radio-devices which are to be prevented from twisting or, in other words, from describing a rotary movement about their own axes. The continuous rotation of the carriers with the aid of gear-wheels renders possible an extraordinarily high efficiency of the machines in conjunction with long life.

The invention has been represented, by way of example, in the drawings, in which Fig. 1 is a top-view of a machine constructed in accordance with the invention, whereas

Fig. 2 represents an enlarged part sectional view of the machine in accordance with Fig. 1.

In the drawing 1 represents a stationary central post or bearing member attached to the base-plate 1a, while 2 designates a wheel-body which is journaled on said member 1 and provided with a rim-gear 3 and a rim-gear 4. 5 is a carriage supporting a carrier 6 capable of rotation about an axis eccentric to the central bearing member 1. The carriage 5 is movable circumferentially along a track 7 which is curved centrically to the centre of the machine. The carriage 5 is provided with teeth 8, which effect an operative connection with the rim-gear 3 through the medium of bevel-wheels 3a, mounted on the support of the track 7, in such a manner, that the carriage 5 moves in the opposite di-

rection to the rotation of the rim-gear 3 when the latter is turned. Upon the carrier 5 and capable of rotation within the carriage 5, a sleeve 9 has been provided carrying a gear-wheel 10 meshing with the rim-gear 11 co-axial with the rim-gears 3 and 4. The gear-wheel 10 is made to support a dual gear-wheel 12, 13 of which the wheel 12 is larger than the gear-wheel 13. The gear-wheel 12 engages in a gear-wheel 14 which is rigidly connected with the sleeve 9, whilst the gear-wheel 13 is made to engage in a gear-wheel 15 located on the carriage or support 5 and non-rotatable relatively thereto. The rim-gear 11 is formed upon the wheel-body 16 which by means of the bevel-wheel 17 is rotated in the same direction as the wheel-body 2, but at a different speed. The wheel-body 16 supports a dual tooth-wheel 18, 19, of which the wheel 18 meshes with the rim-gear 4, while the gear-wheel 19 engages in a gear-wheel 20 also supported by the wheel-body 16. 21 is a ring supported by rollers 21a, of which only one roller is shown and which in their turn are supported by the part 16a, shown as integral with the wheel-body 16. The ring 21 provided with internal and external teeth is caused to travel in a circular path round the centre of the machine through the medium of its internal teeth and the gear-wheel 20, whilst it engages with its external teeth in a further gear-wheel 22 also supported by the part 16a of the wheel-body 16. The gear-wheel 22 is rigidly connected with a carrier 24 with the aid of a sleeve 23. In this way the gear-wheels 19, 20 and 22 in conjunction with the toothed ring 21 have been rendered capable of turning the carrier 24 round the axis of its sleeve 23. The thread is drawn from the spool of the carrier 24 through the sleeve 23 and subsequently guided to the braiding point 26 with the aid of thread-guides, of which only the guiding rollers 25 are shown in the drawings, and which are actuated in a manner well known in this art. That is to say, the yarn is situated about the carriers 6 as to pass alternately above and below them. The thread-guides 25 are adapted to pass the thread of the carrier 24 at certain times, as shown in Fig. 2,

below the spool of the carrier 6 and then again to lift it above this spool. The carrier 6 has further been provided with a disk 27 of circular shape intended and suitable 5 for keeping the thread always away from the rim of the gear-wheel 10. In the track 7 and the rim-gear 11 notches or gaps 28 may be provided, in which the thread may find a place when in its lowermost position. The 10 rollers 21a have been designed in the shape of an obtuse cone in such a manner, that the apex of the cone is made to approximately coincide with the central axis of rotation of the machine. The thread of the spool of the 15 carrier 6 is also passed to the braiding point 26, through the sleeve 9. When the wheel 10 is moving along the gear-rim 11, it will cause the dual wheel 12, 13 to describe a rotary movement round the axis of the carrier 20 6. The rotation of this carrier 6 is the result of the movement of the gear-wheel 13 along the gear-wheel 15 fixed to the carriage 5, whereby the gear-wheel 12 is also rotated, causing in its turn the gear-wheel 14 and 25 simultaneously the carrier 6 to rotate about the axis of the sleeve 9. Preferably the gear-wheel ratios are so chosen, that with each travel or revolution of the spools round the central axis of the machine, the carriers 6 30 and 24 will perform a single revolution about their axes of rotation. As explained in the introductory part of this specification, the purpose of this rotation of the carriers about their individual axes is to compensate or neutralize 35 the twisting of the thread resulting from the revolution or travelling of the carrier about the center of the machine. The rotation of the carriers about their individual axes must, of course, be in the proper direction to effect such compensation or neutralization of the twist, so that the resulting article will have no longitudinal twist. A single revolution of the carriers about their individual axes, in the proper direction, must 40 be employed in order to obtain such neutralization, since if the revolution of a carrier about its own axis were more or less than a single revolution, the twist due to the bodily travel of the carrier about the center 45 of the machine would not be compensated. If required, however, the gear-wheel ratio may be so chosen, that any additional rotation or counter-rotation may be imparted to the material it is intended to braid. 50

55 The gear-wheels 3a, situated between the rim-gear 3 and the teeth 8 of the carriage are mounted rotatably on the support of the track 7.

60 I claim:—

65 1. In a round braiding machine, a carrier, adapted to rotate round an axis and to travel in a circular path about the centre of the machine, a gear-wheel concentric to the axis of rotation of the carrier and means, adapted

of the carrier about the centre of the machine, a single rotation in such a direction as to neutralize the twist resulting from the rotation of the carrier about the center of the machine. 70

2. In a round braiding machine in accordance with claim 1, a rim-gear concentric to the centre of the machine, which is arranged to turn said gear-wheel. 75

3. In a round braiding machine in accordance with claim 1, a rim-gear concentric to the centre of the machine, a second gear-wheel engaging in the rim-gear, means between the said gear-wheels for the purpose of transmitting the movement of the second gear-wheel to the first gear-wheel, and further means adapted to lead and to receive a thread without damaging it, when it is situated between the rim-gear and the second gear-wheel. 80

4. In a round braiding machine in accordance with claim 1, a support for the rotatable carrier, a further gear-wheel located on said support and non-rotatable relatively thereto, two further gear-wheels rigidly connected with each other, one of which is arranged to engage in the gear-wheel concentric to the axis of rotation of the carrier, and the second in the non-rotatable gear-wheel upon the support of the carrier, and means for causing the gear-wheels rigidly connected with each other to circle round the non-rotatable gear-wheel. 85

5. In a round braiding machine in accordance with claim 1, a support for the rotatable carrier, a gear-wheel located on said support and non-rotatable relatively thereto, two further gear-wheels rigidly connected with each other, one of which meshes with the gear-wheel concentric to the axis of rotation of the carrier and the second with the non-rotatable gear-wheel upon the support of the carrier, and a further gear-wheel for causing the gear-wheels rigidly connected with each other to travel round the non-rotatable gear-wheel. 90

6. In a round braiding machine in accordance with claim 1, a support for the rotatable carrier, a gear-wheel located on said support and non-rotatable relatively thereto, two further gear-wheels rigidly connected with each other, one of which is arranged to engage in the gear-wheel concentric to the axis of rotation of the carrier and the other in the non-rotatable gear-wheel upon the support of the carrier, a rim-gear concentric to the shaft of the machine and a further gear-wheel engaging in this rim-gear, which is arranged to support the gear-wheels connected with each other and to cause them to travel round the non-rotatable gear-wheel. 105

7. In a round braiding machine in accordance with claim 1, a support for the rotatable carrier, a gear-wheel located on said

support and non-rotatable relatively thereto, two further gear-wheels rigidly connected with each other, one of which is arranged to engage in the gear-wheel concentric to the axis of rotation of the carrier, whereas the second wheel is made to engage in the non-rotatable gear-wheel upon the support of the carrier, a rim-gear concentric to the axis of the machine, and, engaging in this rim-gear, a further gear-wheel arranged to support the gear-wheels connected with each other and to cause them to travel round the non-rotatable gear-wheel, these two connected gear-wheels having different diameters.

8. In a round braiding machine two rows of carriers circling in opposite directions round the centre of the machine, and means adapted to rotate each carrier of each row continuously about its individual axis.

9. In a round braiding machine in accordance with claim 8 gear wheels for rotating each of the carriers of each row about its individual axis as said rows circle about the center of the machine.

10. In a round braiding machine, a carrier which is adapted to rotate about an axis and to circle about the centre of the machine, a gear-wheel concentric to the axis of rotation of the carrier, further gear-wheels, a ring with internal and external teeth arranged concentrically to the centre of the machine, adapted to travel about the centre of the machine and further adapted in conjunction with said gear-wheels to rotate the gear-wheel concentric to the axis of rotation of the carrier.

11. In a round braiding machine in accordance with claim 10, a roller as support for the movable ring.

12. In a round braiding machine, a plurality of carriers each adapted to rotate about an axis and to circle round the centre of the machine, a gear-wheel concentric to the rotation of each of the carriers, a ring with internal and external teeth arranged concentric to the centre of the machine, said ring being adapted to travel round the centre of the machine and to engage said gear-wheels, and further gear-wheels adapted to actuate said ring.

13. In a round braiding machine in accordance with claim 12, rollers as supports for the movable ring.

14. In a round braiding machine, two series of spool carriers adapted to circle round the centre of the machine in opposite directions and to rotate about their own axes, a gear wheel associated with each carrier and situated concentrically to the axis of rotation of the carrier and rigidly connected with the latter, means for continuously rotating the gear-wheels of the several carriers, a thread-guide for each of the threads of one series of carriers, a rim-gear concentric to the centre of the machine, a gear-wheel for each carrier

of the other series of carriers, such gear-wheel engaging in said rim-gear, and means interposed between the last mentioned gear-wheels and the rim-gear and adapted to lead and to receive a thread from one spool of the first series of carriers without damaging it when it is situated between this gear-wheel and the rim-gear.

15. In a round braiding machine in accordance with claim 14, means between the drive of the machine and the gear-wheels attached to the carriers for the purpose of positively transmitting to said wheels the movement imparted to the machine.

16. A round braiding machine in accordance with claim 8, in which the means for rotating the carriers about their individual axes is so constructed as to give each carrier a single rotation during a revolution of the carriers about the center of the machine.

17. In a round braiding machine, a carrier mounted to rotate about an axis and also to travel in a circular path about the center of the machine, and means, operated by such travel of the carrier, for giving said carrier, during a complete revolution about the center of the machine, a single rotation about said axis in such a direction as to neutralize the twist resulting from the rotation of the carrier about the center of the machine.

In testimony whereof I affix my signature.
GUIDO HORN.
